DISPENSING APPARATUS

Herbert P. Folker, Oakland, Calif., assignor to
National Safety Appliance Co. Ltd., San Fran-
cisco, Calif., a corporation of California

Application September 27, 1937, Serial No. 165,921

11 Claims.

(Cl. 225—2)

This invention relates generally to apparatus for use in dispensing various liquids, and particularly carbonated beverages such as beer.

It is conventional practice to store and transport beer and like carbonated beverages in kegs or like containers, provided with couplers to which dispensing apparatus can be attached. The coupler has an opening, which is normally closed by a cork, and in applying the dispensing apparatus provision is made to dislodge the cork, whereby the liquid is caused to flow by gas pressure to an external faucet.

The present invention is an improvement in apparatus of the above character. It incorporates a fitting which can be readily attached to a keg coupler, and which during a dispensing period is at the lower end of the keg, whereby the beer or like liquid flows downwardly through the fitting. More particularly it is an object of the present invention to provide apparatus of this type, which can be more conveniently applied to a keg of beer by an operator, without release of the gas naturally existing within the keg.

Another object of the invention is to provide dispensing apparatus of the above character, which after being applied to a keg, can be positioned together with the keg in final dispensing position, with connections to an external source of gas under pressure.

Another object of the invention is to provide a novel form of fitting which can be readily attached to the coupler, and in which all of the necessary liquid-tight seals can be established by turning a single member.

Further objects of the invention will appear from the following description in which the preferred embodiment of the invention has been set forth in detail in conjunction with the accompanying drawing.

Referring to the drawing:

Fig. 1 is a side elevational view, in cross section, illustrating apparatus incorporating the present invention, applied to a beer keg and in final dispensing position.

Fig. 2 is a cross sectional detail, taken along the line 2—2 of Fig. 1.

Fig. 3 is a cross sectional detail taken along the line 3—3 of Fig. 1.

In the drawing I have shown portions of a beer keg 10, which in this instance is of the metal type. On one end of the keg there is a metal coupler 11, and this coupler has a central opening 12. As such kegs are delivered from a brewery, opening 12 is sealed by a cork or like removable closure. The coupler 11 may vary as to details,

but the type illustrated is used comparatively universally. It includes a sleeve portion 13, provided with the flanges 14. The ends of these flanges are separated by the slots 16.

My apparatus makes use of a fitting designated generally at 17, which can be quickly attached to the coupler 11. The particular type of fitting illustrated consists of an inner body 18, loosely surrounded by an outer sleeve 19. One side of the body 18 connects with a pipe 21 leading to the dispensing faucet 22.

One end face 23 of the body 18, is adapted to be sealed with respect to the opposed end face 24 on coupler 11, by means of the intervening resilient washer 26. The corresponding end portion of the sleeve 19 is provided with turned lugs 27, adapted to engage the flanges 14 of the coupler. The opening or passage 28 in body 18, directly communicates with and is aligned with the opening 12 of the coupler, and also communicates with pipe 21, through the side extension 29.

Extending through the passage 28 in the fitting, there is a pipe 31 which serves to conduct gas under pressure into the keg. The upper end of pipe 31 is shown provided with the gas ports 32, and a small check valve 33. The representative type of check valve illustrated consists of a disc 34, bearing upon the annular seat 35. When pressure is applied to the pipe 31 in excess of the pressure existing within the keg, then differential gas pressure opens the check 33. However, when the pressure within the pipe 31 is less than the pressure within the keg, the valve member 34 is closed upon its seat and will not permit the escapement of gases from within the keg out through the pipe 31.

Attached to the lower and outer end of the pipe 31, there is a sleeve 37, which in turn is provided with a knurled engaging portion 38. The lower end of the fitting body is provided with a counter bore 39, which slidably accommodates a follower 41. Suitable means prevents rotation of the follower 41 with respect to the fitting, as for example the follower can be provided with a stud 42, engaging within a slot 43 formed in the body 18. The follower is also provided with an annular flange 44, and this flange is engaged by a flange 46, formed on a nut 47. Nut 47 has threaded engagement with the adjacent end of the sleeve 19.

The inner end face 48 of the follower 41, is shown engaging one side of a resilient sealing washer 49. The upper side of this washer is adapted to seal against the opposed annular shoulder 51, formed within the body 18. Washer 49 can be made of resilient vulcanized rubber,

or a synthetic rubber like "Duprene", and washer 26 can be made of similar material. Sleeve 31 has detachable threaded engagement 52, with the follower 41, whereby an operator by turning the knurled portion 38, can detach pipe 31 from the remainder of the assembly. The inner end of this sleeve may also have sealing engagement with washer 49.

Portions of additional equipment used with the apparatus described above, have also been illustrated. Thus the dispensing pipe 21 is shown extending through the front wall 56, of a compartment 57 which if desired can be refrigerated. Extending upwardly through the bottom wall 58, of this compartment, there is a fitting 59, connected with a source of gas under pressure, such as carbon dioxide. The upper end 61 of the fitting 59 is accommodated within an opening 62 formed in the sleeve 31, and a gasket 63 forms a sealed gas-tight engagement between these parts. A suitable type of check valve is provided within the fitting 59, which is opened by depression of the valve stem 64. With the fitting occupying a position within the sleeve 31, as shown in Fig. 1, valve stem 64 is depressed by the pin 66, which is carried by the apertured disc 67. Instead of providing a compartment for housing the keg, any suitable supporting means can be used to carry the keg and associated parts in the position shown.

Use of the apparatus described above can be outlined as follows:—As previously pointed out the type of keg to which the apparatus can be applied, normally has the opening 12 of the coupler 11 closed by means of a cork. The operator takes the fitting 17 and first loosens the nut 47. Lugs 27 are then engaged with the coupler, by first causing these lugs to pass through slots 16, and then by turning the fitting with respect to the coupler until the lugs 27 properly engage over the flanges 14, in the manner illustrated in Fig. 1. Nut 47 is then tightened to apply clamping force upon the sealing washers 26 and 49. Up to this time the pipe 31 has been detached with respect to the fitting. The operator now takes this pipe and forces it through the fitting 17. The opening provided in sealing washer 49 is normally slightly smaller than the external diameter of the pipe, so that the fit of the pipe within the washer is sufficiently tight to form a seal. When the inner end of the pipe engages the cork in the coupler 11, sufficient force is applied to dislodge the cork, whereby the pipe can then be moved to the final operating position illustrated in Fig. 1. Assuming now that the operator has engaged the threaded connection 52, the keg is positioned within the refrigerator compartment or like auxiliary equipment, to effect an engagement with the fitting 59, as shown in Fig. 1. The upper end of the pipe 31 is now at the upper end of the keg, whereby gas pressure introduced through the pipe from the fitting 59, enters the space above the liquid and thereby displaces the liquid downwardly. It will be seen that if faucet 22 is opened the liquid flows downwardly through opening 12, about the pipe 31, and thence through pipe 21, to the faucet.

It will be evident from the foregoing that my apparatus can be readily applied to kegs and like liquid containers, without danger of permitting escape of gas. As the pipe 31 is thrust into the keg, the check valve 33 is closed and therefore there is no danger of gas escaping from the beer, even though at this time the exterior end of the pipe is not connected to a source of gas under

pressure. When the apparatus is in the final operating position shown in Fig. 1, the check valve may be occasionally utilized, to prevent back flow of gas, in the event of failure of the gas supply attached to fitting 59.

I claim:

1. In dispensing apparatus for use with a liquid container, the container being of the type provided with a coupler having a discharge opening therein, a fitting adapted to be detachably connected to and mounted on said coupler, a liquid discharge pipe communicating with the fitting, the fitting being provided with a passage aligned with said opening, a pipe adapted to be removably disposed within said passage with one end portion of the pipe extending through said opening into the container, the outer end of the pipe being adapted for connection with a source of gas under pressure, and a check valve carried by the inner end of said pipe, said check valve closing against pressure within the container, and being opened by gas pressure applied to said pipe.

2. In dispensing apparatus for use with a liquid container, the container being of the type having one wall of the same provided with a coupler, the coupler having a discharge opening, a fitting adapted to be detachably connected to and mounted on said coupler, a liquid discharge pipe communicating with the fitting, the fitting being provided with a passage aligned with said opening, a pipe adapted to be disposed within said passage, with one portion of the pipe extending through said opening into the container, the outer end of the pipe being adapted for connection with a source of gas under pressure, exterior of the fitting, means for effecting a seal between said fitting and said pipe, said seal permitting longitudinal sliding movement of the pipe through the fitting, and a check valve carried by the inner end of said pipe, said check valve closing against pressure within the container but being opened by gas pressure applied to said pipe.

3. In a dispensing apparatus for use with a liquid container, the container being of the type provided with a coupler having an opening therethrough, a fitting adapted to be detachably connected to and mounted on said coupler, a liquid discharge pipe communicating with said fitting, the fitting being provided with a passage aligned with the aforementioned opening, a pipe adapted to be disposed within said passage, with a portion of the pipe extending through the aforementioned opening into the container, the outer end of the pipe being adapted for connection with a source of gas under pressure, means forming a seal between the fitting and said coupler, means forming a seal between the pipe and said fitting, and common means for applying clamping forces to both said sealing means.

4. In a dispensing apparatus for use with a liquid container, the container being of the type provided with a coupler having an opening therethrough, a fitting adapted to be detachably connected to and mounted on said coupler, a liquid discharge pipe communicating with said fitting, the fitting being provided with a passage aligned with the aforementioned opening, a pipe adapted to be disposed within said passage, with a portion of the pipe extending through the aforementioned opening into the container, the outer end of the pipe being adapted for connection with a source of gas under pressure, means forming a seal between the fitting and said coupler, means forming a seal between the pipe and

said fitting and means including a nut concentric with said pipe and threaded upon the fitting, for applying clamping forces to the seal between the fitting and the coupler.

5. In a dispensing apparatus for use with a liquid container, the container being of the type provided with a coupler having an opening therethrough, a fitting adapted to have detachable connection with said coupler, a liquid discharge pipe connected to said fitting, and means for establishing connection between said fitting and a source of gas under pressure, said last means including a second fitting connected to a source of gas under pressure, a check valve in said second fitting, means for making sealing engagement between said fittings, and means carried by the first fitting for opening said check valve as said fittings are brought into sealing engagement.

20. In a dispensing apparatus for use with a liquid container, the container being of the type provided with a coupler having an opening therethrough, a fitting adapted to have detachable connection with said coupler, a liquid discharge pipe connected to said fitting, and means for establishing connection between said fitting and a source of gas under pressure, said last means including a second fitting connected to a source of gas under pressure, the first fitting having a socket to receive the second fitting, a check valve in the second fitting, means forming sealed engagement between the fittings as the same are urged into physical engagement, and means carried by the first fitting for opening said check valve as said fittings are urged into physical engagement.

40. In a dispensing apparatus for use with a liquid container, the container being of the type provided with a coupler having an opening therethrough, a fitting adapted to be detachably mounted upon the coupler and having means for establishing sealing contact with the outer face of the coupler, a liquid discharge pipe connected to the fitting, the fitting having a passage therethrough in alignment with said opening, and an elongated member adapted to be thrust through said passage to dislodge a closure in said opening.

45. In a dispensing apparatus for use with a liquid container, the container being of the type provided with a coupler having an opening therethrough, a fitting adapted to be detachably mounted upon the coupler, means carried by the fitting for establishing sealing contact with the outer face of the coupler, a liquid discharge pipe connected to the fitting, the fitting having a passage therethrough in alignment with said open-

ing, an elongated member adapted to be thrust through the passage in the fitting to dislodge a closure in said opening, means forming a seal between the fitting and said member, said member being so proportioned that when it extends through said opening, liquid from the container may flow into the fitting through the opening and about said member.

5. In a dispensing apparatus for use with a liquid container, the container being of the type provided with a coupler having an opening therethrough, a fitting adapted to be mounted and have detachable connection with said coupler, a liquid discharge pipe connected to said fitting, and means for establishing connection between said fitting and a source of gas under pressure, said least means including a second fitting connected to a source of gas under pressure, a check valve in said second fitting, means for making sealing engagement between said fittings, and means for automatically opening said check valve as said fittings are brought into sealing engagement.

10. In a dispensing apparatus for use with a liquid container, the container being of the type provided with a coupler having an opening therethrough, a fitting adapted to be detachably mounted upon said coupler, means carried by said fitting for making sealing engagement with the outer face of said coupler, a liquid discharge pipe connected to said fitting, and means for establishing connection between said fitting and a source of gas under pressure, said last means including a second fitting connected to a source of gas under pressure, a check valve in said second fitting, means including a gasket surrounding the second fitting for making sealing engagement between said fittings, and means for automatically opening said check valve as said fittings are brought into sealing engagement.

15. In a dispensing apparatus for use with a liquid container, the container being of the type provided with a coupler at its one end having a discharge opening therethrough, a fitting adapted to be detachably connected to said coupler, a liquid discharge pipe communicating with the fitting, the fitting being provided with a passage which is aligned with said opening, and a pipe adapted to be disposed within said passage, with one portion of the pipe extending through said opening into the container, the outer end of the pipe being adapted for connection with a source of gas under pressure, said pipe being of such length that its inner end terminates near the opposite end wall of the container.

20. HERBERT P. FOLKER.
